HYDROSTATIC BAILER

William A. Larson and Harry T. Swortwood,
Oklahoma City, Okla.

Application December 15, 1936, Serial No. 115,903

9 Claims. (Cl. 166—19)

This invention relates to bailers, or well clean out tools, and more particularly to pressure type or hydrostatic bailers in which the underground pressure is utilized to fill the bailer with the material which is to be bailed.

The chief object of the invention is to provide a bailer of this type, the operating parts of which do not obstruct the passageway from the inlet end of the bailer into the load chamber, and which, because of this feature, will fill much faster than other bailers, will freely permit the entrance of large pieces of material and because of the higher speed of the entering fluid will pick up a greater percentage of sand or other material at each loading.

Other objects of the invention are to provide improved means for retaining and replacing the frangible seal between the air chamber and the load chamber; to provide means for completely shattering the frangible disc by pressure created by the bailer itself, together with additional mechanical means for breaking the disc in case the pressure means fails, and which mechanical means will not obstruct the passageway between the air chamber and the load chamber, and will prevent parts of the broken disc from obstructing the passageway; to provide a bailer which has a greater effective passage area between the entrance chamber and the load chamber; to provide improved means for relieving the pressure within the bailer as it rises toward the earth's surface, which means is much less likely to become clogged than the relief means used on other bailers of this type; to provide a bailer so constructed that the shoe may be easily and quickly replaced by a different type shoe without the necessity of taking the entire bailer apart; to provide an improved frangible disc which acts as a means for preventing underground pressure from unseating the gasket on which said disc is seated; to provide a bailer so constructed as to eliminate the accidental breakage of the frangible sealing disc before the bailer is in operating position in the well; and to provide a construction which greatly simplifies the emptying of the bailer after it is withdrawn, full, from a well; and which provides a greater effective passage area for emptying the bailer.

Other objects will be apparent to the reader of the following specification.

Referring to the drawings:

Figure 1 is a side elevation of the bailer complete;

Figure 2 is a side view of the sub or bailer head

partially in section, and is taken along the line 2—2 of Fig. 1;

Figure 3 is a side sectional view of the lower portion of the bailer, and is taken along line 3—3 of Fig. 1;

Figure 4 is a side elevation of a portion of the device showing the manner of retaining the frangible disc in position, as well as the means for locking the upper and lower portions of the bailer together;

Figure 5 is a side view of the lower portion of the bailer partially in section to show the "open" position of the check valve after the frangible disc has been broken; and,

Figures 6, 7 and 8 are horizontal sections taken along the lines 6—6, 7—7, and 8—8 respectively of Fig. 3, and illustrate respectively the manner of locking the upper and lower sections of the casing together, the manner of locking the plunger within the lower portion of the casing; and the manner of limiting the movement of the plunger within the casing.

Like characters of reference designate like parts in all the figures.

It is understood that various changes in the form, proportion, size, shape, weight, material and other details of construction, within the scope of our invention may be resorted to without departing from the spirit or broad principle of our invention and without sacrificing any of the advantages thereof; and it is also understood that the drawings are to be interpreted as being illustrative and not restrictive.

Referring to the parts, the entire bailer housing is designated by the numeral 11, and is comprised of a sub or bailer head 12, a central casing member 13, a coupling 14, a lock section 15, and a plunger section 16, all of the same exterior diameter.

The sub 12 carries suitable means 17 for attaching it to a string of tubing or other means 18 for lowering the bailer into a well, and the lower end of the sub is secured to the section 13 (Fig. 2) by suitable means, as by a plurality of rivets 19. A relief valve is set into the body of the sub in a bore 20 which affords atmospheric communication with the bore 21 in the lower end of the sub 12. The relief valve is composed of a set member 22, a head with stem attached 23, and a plural winged guide member 24, into which the stem is centrally screwed. The weight of the head and the guide member normally holds the valve closed. Its office will be hereinbelow explained.

The coupling 14 is male at both ends, and is

attached to the lower end of section 13 by means of threads (Fig. 3). The lower end of coupling 14 is smooth and cylindrical, and is removably secured within the upper end of lock section 15 by means of spaced L-shaped slots 25, 26 and 27, their upper ends opening from the upper end of lock section 15, and cooperating with suitably sized lugs 28, 29 and 30 made integral with the lower end of coupling 14. After the coupling 14 and lock section 15 are in assembled relation and the lugs 28, 29, and 30 are positioned respectively in the lower ends of slots 25, 26 and 27, as is the lug 28 in the slot 25 of Fig. 1, a screw plug 31 is screwed into the wall of the coupling 14 through one of the slots 25, and as clearly shown in Fig. 1 prevents relative rotational movement between the coupling 14 and lock section 15, thus locking the two together. The plug 31 seats in an offset portion 32 integral with the wall of the coupling 14, and when tightened its head is substantially flush with the outer surface of lock section 15.

The extreme lower end of coupling 14 (Fig. 3) is slightly reduced in diameter and is threaded to receive a skeleton cap 33. This cap serves to firmly hold a frangible disc 34 in position on the lower end of the coupling. The disc 34 has an annular flange 35, the outer surface of which serves to hold in position a resilient gasket 36, which in turn serves as a seal between the rim of the disc and the end of the coupling. The cap, disc, and gasket thus serve to complete an air tight load chamber 37 in the upper portion of the bailer.

35 The lower end of the lock section 15 (Fig. 3) is reduced slightly in interior bore and in outside diameter, the outside being threaded to receive the upper end of the plunger section 16. The lower end of the lock section which fits inside the section 16 forms an annular shoulder 38 inside the bore of the plunger section 16, and the bore of section 16 is abruptly reduced near the lower end to form an additional internal shoulder 39. The office of these shoulders will 40 be hereinbelow explained.

A plurality of longitudinal slots 40, 41 and 42 (Figs. 7 and 8) are formed in the lower end of the section 16. The depth of these slots is substantially the same as the reduction in the bore 50 of the lower end of the section, and they run from the shoulder 39 to the lower end of the section 16. Their purpose is to permit the entrance of a hollow plunger 43 into the lower end of the section 16. The plunger 43 carries a like plurality of integral lugs 44, 45, and 46, suitably sized, and spaced identical to the spacing of the slots. The plunger may be inserted into the section 16, its upper end passing into the bore of the lock section 15, and when its lugs 60 have reached the enlarged bore in the section 16 it may be partially rotated to the position shown in Fig. 7, in which position the lugs 44, 45 and 46 rest on the shoulders between the slots, thereby limiting the outward movement of the plunger 43. To maintain this relative position between the plunger 43 and section 16, two substantially opposed longitudinal slots 47 and 48 are formed through the wall of the plunger, below the lugs. The smooth ends of a pair of screw plugs 49 and 50 respectively extend partially into these slots 47 and 48, as shown in Fig. 3. The plugs are seated in threaded perforations in the wall of the section 16, and prevent rotational movement between the plunger and 75 lock section 16, but the slots 47 and 48 permit

limited longitudinal movement of the plunger into the section.

To prevent the accidental movement of the plunger to the inner end of its limited stroke, a heavy coil spring 51 is positioned in the space between the plunger and the wall of section 16. One end of the spring bears on the shoulder 38, and its other end bears on the upper surface of lugs 44, 45 and 46. The wall of section 16 has a plurality of through perforations 52, which permit the entrance of fluid into the annular space between the plunger and section 16, thus serving to wash out any sand particles which might otherwise lodge in this space and prevent efficient operation of the device.

The upper end of the plunger 43 carries a hinged one way gate valve 53, adapted to open only toward the load chamber 37, and is freely opened by upward pressure. The diameter of the valve 53 is slightly less than the diameter of the bore 2 in the lower end of the coupling 14, so that when the frangible disc is broken, the valve may open into the lower end of the coupling 14 (as in Fig. 5) and lie along the wall of the coupling, leaving substantially the entire area of the bore open 2 for the passage of fluid into the load chamber 37. The plunger is of a diameter to fit snugly within the bore of the section 16, and creates considerable pressure in the confined space immediately below the frangible disc 34, as it is 30 moved toward the disc. The interior wall of the coupling 14 has an indentation of a size and shape to partially receive the central projection 54 (as in Fig. 5) formed on the upper surface of the valve 53.

The lower end of the plunger 43 is in the form of a hollow shoe 55, which has a plurality of side inlets 56 and 57 through its side walls.

The assembly of the various parts has been explained as the description has progressed. The 40 operation will now be explained.

Operation

With the frangible disc properly seated on the lower end of the coupling 14, the bailer is lowered into a well by a cable, string of tubing, or other suitable means 58. As it penetrates into the well the exterior pressure increases. Due to this pressure the relief valve 23 remains tightly closed and prevents air or fluid 50 from entering the chamber 37, since its lower end is also sealed. The air inside the load chamber, therefore, remains at atmospheric pressure. The greater underground pressure is free to enter the space immediately below the disc 34, 55 however, through the valve 53. When fluid is encountered the tension of the spring 51 prevents the plunger from moving inward in the casing and prematurely shattering the disc 34. When the shoe 55 contacts the sand or other 60 material which is to be cleaned from the well the entire weight of the bailer (approximately 1,000 pounds) is transferred to the plunger, forcing the plunger toward the disc 34 against the tension of spring 51. At this time fluid is, 65 of course, present inside the casing above the valve 53 and below the disc, and the pressure upward on the disc is great. The added pressure caused by the movement of the plunger is practically always sufficient to completely shatter 70 the disc before the projection 54 ever touches the disc. If a very shallow well is being cleaned a lighter disc is used. In any event the valve 53 is forced through the space previously occupied by the disc, and as it enters the load 75

chamber 37 (Fig. 5) completes the shattering of the disc, leaving no pieces of the disc projecting into the chamber to obstruct the passage of sand and liquid into the chamber. All this action is practically simultaneous, and with the breaking of the disc the fluid and sand rush past the valve 53 into the load chamber 37, which was at atmospheric pressure until the disc broke. The load chamber is filled almost immediately, the sand laden fluid entering through the central bore of the plunger as well as through the side inlets 56 and 51.

The bailer may then be withdrawn from the well. As it rises toward the earth the expansion inside the load chamber, due to the lessening of the pressure, is taken care of by the relief valve 23, which we prefer to construct sufficiently large (as shown) that it cannot be easily clogged by sand, particles of rock, or other material.

After the bailer is withdrawn from the well, the screw plug 31 is unscrewed, the section 15 is partially rotated so that the lugs 28, 29 and 30 may pass out of the slots 25, 26 and 27, and the bailer is separated at this point, permitting the sand laden fluid to pass out of the load chamber.

The cap 33 is then unscrewed, the gasket removed and replaced on a new frangible disc 34, and the disc is secured in position on the lower end of the coupling 14, again sealing the lower end of the load chamber 37. The two parts of the bailer are again assembled in a manner evident from the above description, and the bailer is again ready to enter the hole.

We call attention particularly to the unobstructed entrance to the load chamber after the frangible disc is broken, to the simple manner of completely emptying the load chamber and replacing the frangible disc, to the efficient manner of positively sealing the lower end of the load chamber without possibility of the gasket being forced from its seat by underground pressure, to the simple manner of replacing or substituting a plunger or shoe, to the unobstructed flow area of the passageway leading upward to the lower end of the load chamber, and to the means for preventing the accidental and premature breakage of the frangible disc when fluid or any other obstruction suddenly creates a resistance to the downward travel of the bailer.

While we have described and illustrated a specific embodiment of our invention we are aware that numerous alterations and changes may be made therein, and we do not wish to be limited except by the prior art and the scope of the appended claims.

We claim:

1. A hydrostatic bailer comprising: a casing closed at one end; a removably positioned frangible member within the casing dividing its interior into two chambers; a hollow plunger in one of the chambers mounted for limited longitudinal movement therein, and of sufficient length to extend outside said casing when it is at the inner end of its limited movement; and a check valve mounted on the inner end of said plunger adapted to permit the passage of fluid into said casing and to prevent its passage outward therefrom.

2. Organization as described in claim 1, and spring means for retarding the rapid movement of the plunger into said casing.

3. A hydrostatic bailer comprising: a first casing member having one of its ends reduced in diameter and closed by a removably secured frangible member; a second casing member adapted to receive telescopically the reduced and closed end of said first casing member; lugs and slots cooperatively carried respectively by the two casing members for locking the one end of hollow plunger mounted for limited longitudinal movement within the unobstructed portion of the second casing member; and an inwardly opening check valve for controlling the flow of fluid through said plunger; said plunger adapted, when moved toward the closed end of said first casing, to create sufficient pressure to break said frangible member, thus opening a passageway from the interior of said second casing to the interior of the first casing.

4. In a hydrostatic bailer, a means of sealing the inner end of the load chamber casing comprising a frangible circular disc having an inwardly projecting annular concentric flange on one of its sides adapted to fit just inside the end rim adjacent said flange adapted to seat on the end of said casing, and having an integral concavo-convex circular central portion; and an internally threaded disc holding member having a centrally projecting annular rim at one of its ends, said rim adapted to contact the rim of said frangible disc and to hold it tightly against the end of said casing when the holder is screwed on the end of the casing.

5. Organization as described in claim 4, and an annular resilient gasket for sealing between the end of said casing and the rim of said frangible disc.

6. A hydrostatic bailer comprising: a casing closed at one end; a removably positioned frangible member within the casing dividing its interior into two chambers; a hollow plunger in one of the chambers mounted for limited longitudinal movement therein, and of sufficient length to extend outside said casing when it is at the inner end of its limited movement; a check valve mounted on the inner end of said plunger adapted to permit the passage of fluid into said casing and to prevent its passage outward therefrom; and a relief valve in the casing above the frangible member.

7. A hydrostatic bailer comprising: a casing closed at its upper end; a removable frangible disc within the casing for dividing its interior into two chambers; and a hollow plunger mounted for limited longitudinal movement within the open end of said casing, and having an inwardly opening check valve mounted on its inner end; said check valve adapted, when said plunger is at the inner end of its limited movement to shatter said frangible disc and enter the disc closed portion of said casing, opening flat against the side wall of said casing.

8. Organization as described in claim 7, and spring means for retarding the movement of said plunger toward said disc.

9. Organization as described in claim 7, and a relief valve through the wall of the casing above the frangible disc.
